UNITED STATES PATENT OFFICE.

LOUIS BULASKY, OF BROOKLYN, NEW YORK.

SEWING MACHINE.

Application filed March 13, 1923. Serial No. 624,859.

To all whom it may concern:

Be it known that I, LOUIS BULASKY, a citizen of the United States, residing in the borough of Brooklyn, of the city of New York, in the State of New York, have invented certain new and useful Improvements in Sewing Machines, of which the following is a specification, reference being had to the accompanying drawing, forming 10 a part hereof.

This invention relates to sewing machines of the general character of that shown in Letters Patent of the United States No. 777,074, dated December 13, 1904, which are 15 adapted for the stitching together of straw braids to make hats and for the stitching of wire binding upon the edge of straw, buckram and felt hats, the needle, which reciprocates in a substantially vertical direction, 20 being mounted upon a frame which oscillates upon a horizontal axis so that the needle enters the fabric alternately on opposite sides of a median line, forming, in co-operation with the looper which is correspondingly reciprocated, diagonal or zig-zag 25 stitches. In the operation of the machine shown and described in said Letters Patent it has been found that the output of the machine is somewhat reduced by the 30 time consumed in restoring the gage to position after it has been displaced as is frequently necessary in the operation of the machine and that the operation itself is somewhat slowed down by the necessity of taking pains, on the part of the operator, 35 to prevent the overlapping of two braids which are to be stitched together, as well as by the necessity for the exercise of care, in some classes of work, to prevent the free 40 edge of the material operated upon from curling and riding above the gage. It is the object of the present invention to improve the machine described in said Letters Patent in such manner as to overcome the 45 difficulties referred to and thereby to make possible a greater speed of operation and a greater output. In accordance with the invention there is provided an improved device for preventing the curling of the edge 50 of the work and the rising of the same above the gage. The invention will be more fully explained hereinafter with reference to the accompanying drawings in which—

Figure 1 is a view in front elevation of a 55 zig-zag stitch sewing machine substantially as shown in Letters Patent No. 777,074, but

with the devices which form the subject of the present invention applied thereto.

Figure 2 is a partial view of the same on a larger scale. 60

Figure 3 is a view of the parts shown in Figure 2 as seen from the left hand in Figure 2.

Figure 4 is a detail top view of a gage and retaining finger and its supporting device. 65

As fully described in said Letters Patent, the base *a* of the machine carries a frame *a'* and an arm *a''* which support the working parts of the machine, the main shaft *b* having driving pulleys *b'* and an eccentric *b''*, which, through the pitman *b³*, lever *b⁴* and link *b⁵*, imparts to the needle bar *c* reciprocation in a substantially vertical direction. For the purpose of effecting the zig-zag or cross stitch the needle bar *c* is mounted for vertical reciprocation in a frame *d* which is mounted to oscillate about a horizontal axis and is oscillated by a cam *e'*, driven from the shaft *b*, a lever *f* and a link *f'*, as fully 70 described in said Letters Patent. The presser-foot *g*, feeder *o* and looper *p* are also arranged and operate as shown in said Letters Patent. 75

The material to be stitched rests upon 80 the usual bed plate *n* and is held in engagement with the feeder *o* by the presser-foot *g*, the two braids which are to be stitched together meeting in a line which is median with respect to the two extreme 85 positions of the needle as it is oscillated for the formation of the zig-zag stitch. To prevent the possibility of overlapping of the two braids there is provided, slightly in advance of the position of the needle, a thin 90 separator plate *h*, which, in its working position, stands with its lower end nearly touching the bed plate *n* as shown in Figures 2 and 3. As this separator stands but a short distance in front of the needle there 95 is practically no possibility of the overlapping, before they reach the needle, of the two braids which are to be stitched together. For some classes of work the close 100 proximity of the separator to the bed plate 105 would be undesirable and for this reason and also to permit easy manipulation of the work it is desirable that the separator be capable of movement out of working position. Accordingly it is formed as a part 110 of or is secured to a movable plate *h'*, which is frictionally supported by a fixed plate

h^2 which in turn is secured to the extremity of the arm a^2 , as shown at h^3 . An operating lever h^4 , at one end engaging a notched projection h^5 of the separator carrier h' , is mounted upon the plate h^2 by a pivot screw h^6 , which passes through a vertical guide slot h^7 of the plate h' . By manipulation of the lever h^4 the separator h can be lowered into or raised out of operating position if desired.

The gage i by which the right hand edge of the work is guided in its passage through the machine, preferably bent as at i' for a purpose to be described, is formed as a part 15 of a relatively long arm i^2 which is pivoted, as at i^3 , upon a carrier plate i^4 . The latter is formed with a long horizontal slot i^5 , for engagement with a guide piece n' , secured to the bed plate n , a flanged thumb 20 screw i^6 being provided for the purpose of holding the carrier i^4 in longitudinally adjusted position upon the bed plate n , so that the gage i can be secured in adjusted position with respect to the median line 25 of the needle position. It will be observed that through the pivoting of the gage arm i^2 upon the carrier i^4 the gage can be swung back, as indicated by broken lines in Figure 2, out of operative position whenever the 30 work is to be manipulated, and can be restored at once to its original position, with-

out requiring any readjustment, when the operation of stitching is to be resumed.

With some classes of work there may be at times a tendency of the edge of the work to curl up and to ride over the gage. To prevent this there is mounted on the gage arm i^2 a sliding stop finger k , which may be slotted longitudinally, as at k' , and held to the gage arm i^2 by a bolt and spring 40 pressed washer, as shown at k^2 , the reduced left hand portion of the stop finger being conveniently guided in the bent portion i' of the gage. This stop finger, in operative position, is extended as shown in Figures 45 1, 2 and 4, but may be drawn back out of the way whenever that is desirable in the manipulation of the work.

I claim as my invention:

In a sewing machine of the character described, the combination of a bed-plate, a gage-carrying plate adjustably secured to the bed-plate, a gage and a gage arm pivotally mounted on said plate and bent to form an upward projection, and a stop finger mounted adjustably on the gage arm and extended through the upward projection thereof.

This specification signed this 12th day of March A. D. 1923.

LOUIS BULASKY.
